Inventor:

Freeman A. Green

UNITED STATES PATENT OFFICE.

FREEMAN A. GREEN, OF HAMILTON, ONTARIO, CANADA.

DESIGN FOR A MEMORIAL TABLET.

SPECIFICATION forming part of Design No. 18,019, dated January 17, 1888.

Application filed October 13, 1887. Serial No. 252,972. Term of patent 3½ years.

To all whom it may concern:

Be it known that I, FREEMAN A. GREEN, a citizen of Canada, residing at Hamilton, in the county of Wentworth, Province of Ontario, 5 Canada, have invented and produced a new and original Design for a Memorial Tablet for Parlors, of which the following is a specification, reference being had to the accompanying drawing, forming a part thereof.

10 The drawing shows a front face view or elevation of my newly-designed parlor memorial tablet, this view being deemed necessary to fully illustrate my design.

15 My design is intended to be produced on any suitable material by any suitable method. The leading feature of my design consists of a memorial tablet ornamented with stars, a diamond, and also of a border-line comprising an arched top and rectangular bottom having concaved corners inclosing a space therein.

In the drawing, A is a memorial tablet rectangular in shape, having a border-line, D, comprising an arched top and rectangular bottom with concaved corners, and space B inclosed therein, the decoration-stars *c*, and diamond *e* between the space B and border-line D. 25

I claim—

The design for a memorial tablet herein shown and described, the same consisting of a rectangular tablet, A, having a border-line, D, 30 comprising an arched top and rectangular bottom having concaved corners and space B inclosed therein, the decorative stars *c*, and diamond *e* between the space B and border-line D, as set forth.

FREEMAN A. GREEN.
